UNITED STATES PATENT OFFICE.

JAMES J. SUNDAY, OF DETROIT, MICHIGAN, ASSIGNOR TO STANDARD TUBE & MANUFACTURING COMPANY, OF DETROIT, MICHIGAN, A CORPORATION OF MICHIGAN.

AUTOMOBILE HEATER.

Application filed August 29, 1927. Serial No. 218,045.

This invention relates to an automobile heater, wherein heat is taken from the exhaust gases of the internal combustion engine for the purpose of heating the interior 5 of the automobile.

It is the aim of the invention to provide a heater which affords large heat transferring surface as between the exhaust gases and air to be heated, while the exterior dimensions of the device are such as to form 10 a relatively small and compact heater. It is a further aim of the invention to provide a heater which can readily be placed on cars which do not include heaters as 15 original equipment. Structural features of such cars which include frame, frame cross members, drive shaft, etc. very often make it difficult to put a heater on the car. Accordingly, some of the portions of the heater 20 are made adjustable so that connecting conduits can be arranged to extend in various directions from the heater. Further features of the invention include the simplicity of the heater structure so that it can 25 be manufactured economically and at the same time arrangement is such that undesirable mixing of exhaust gases and air is prevented.

More particularly, the heater of this invention takes the form of a casting which is 30 to be placed in the exhaust line, and around the casting is a shell. The casting has passageways for the exhaust gases and for air, and the shell provides for the passage of 35 air around the casting. By reason of utilizing a casting there is little danger of leakage of exhaust gases into the air being heated. Moreover, the casting is so shaped as to facilitate its formation in a mold.

40 In the accompanying drawings:

Fig. 1 is a perspective view of the heater with parts cut away and parts in section, showing the interior casting unit and the exterior shell, and the passageways for the 45 exhaust gases and air.

Fig. 2 is a horizontal section through a portion of the heater showing the manner in which the passageways and the walls therefor in the casting member are arranged for 50 equal distribution of exhaust gases through the casting.

Fig. 3 is a section on line 3-3 of Fig. 2 showing the preferred formation of certain 55 portions of the casting to facilitate the casting of the same.

The interior member of the heater, which is a casting, is referenced 1, and is provided at one end with an opening 2 and at the other end with an opening 3. This member is designed to be placed in the exhaust line 60 and preferably the arrangement is such that either end can be used as an inlet or outlet. In other words, it is reversible and in making the installation no particular attention may be paid to which end is for the inlet and which end for the outlet. The casting includes longitudinally extending hollow partition-like members 4, which communicate at opposite ends with the openings 2 and 3. Thus the exhaust gases 70 which enter one opening are divided and pass through the hollow member 4 and then leave the casting through the opposite opening. Preferably the arrangement is such as to provide for four of such passageways 75 for the exhaust gases as shown at 5 in Fig. 2.

The central partition member is preferably positioned in advance of the others, so as to more nearly approach the adjacent opening. In this manner the exhaust gases 80 coming into the casting through the opening 2 (Fig. 2) are more or less equally divided by the central partition member and flow to both sides thereof, whereupon the exhaust gases pass through the channels disposed on either side of the central partition member. The combined capacity of the several passageways for the exhaust gases is, at least, equal to or greater than the capacity of the exhaust conduit, so as to permit the gases to readily flow through the casting, without creating any back pressure 85 upon the engine.

Referring to Fig. 3, it will be noted that the several partitions of the casting have 90 their walls tapered from one end to the other, inasmuch as the casting has to be made in a mold and preferably a sand mold. This taper facilitates removal of a casting from a mold without destroying the mold. If desirable the ends of the casting which 95 form the inlet and outlet openings may be split as at 6, and provided with lugs for receiving a tightening bolt 7, so that the same can be somewhat contracted for attachment to a conduit or suitable bushing.

Around this casting member through which the exhaust gases pass in the several passageways, is a secured shell referenced, generally, 10. The shell is of stamped sheet 100

110

metal preferably having a lower part 11 and an upper part 12 secured together by a lock seam 18. Each member 11 and 12 is shaped to conform to the figuration of the interior casting, and the ends of the member designed to make close contact with the inlet and outlet portions of the casting as shown at 14 (Fig. 2). Thus the shell is tightly clamped around the casting member.

10 This construction provides a number of passageways for air which are referenced 15, there being such a passageway between each two adjacent hollow partitions for the exhaust gases, and preferably the shell is 20 spaced in the casting thus to provide additional air passageways 15^a around the outside of the casting.

For the purpose of permitting air to pass 25 through the heater one of the shell members 20 as, for example, the shell member 12, is provided with inlet and outlet openings. Into 30 these openings are fitted devices 16 and 17 for connection with suitable air conducting conduits. The device 16 will be connected 35 to a conduit which conducts fresh air into the heater and the device 17 will be connected to a conduit for conducting the heated air into the interior of the automobile. These devices 16 and 17 are made preferably of two stampings 18 and 19 which 40 are connected together by a lock seam 20. The members 19 are secured to the opening by metal which is extended through the opening and then flanged over as shown at 45 21. The members may be provided with beads 22 lying above the opening so that the devices are nicely positioned.

This construction makes for ease in 50 installation. It will be appreciated that structural features of automobiles vary so that it is oftentimes necessary to put the heater in different positions and to run the air conduits to and from the heater in different directions. The devices 16 and 17 are 55 rotatable at their connections so that they can be positioned in any desired manner as required by the structural features of an automobile, thus to facilitate the installation of the heater.

50 Fresh air coming in through the member 16 passes downwardly through the passageways 15 and 15^a, and for the purpose of insuring this downward movement the casting is provided with a partition member 25, 55 which is preferably an integral part of the casting. The partition member has legs which extend downwardly substantially half the distance of the casting, thus dividing each passageway 15. The partition 60 member also extends above and outside of the casting and makes contact with the portion 12 of the shell, and with the shell at the sides of the device as indicated in Fig. 2. Thus this partition causes incoming air 65 to pass downwardly through the passage-

ways 15 and 15^a whereupon the air assumes a longitudinal direction under the partition and then upwardly through the passageways and out through the device 17. It will be noted that the partition member acts 70 to support the shell at the top and at the sides. This construction aids in preventing the pulsations of the exhaust gases from being telegraphed into the automobile. In other words, it prevents vibration of the 75 outer shell.

The air outlet member 17 is preferably formed with a valve 26 having suitable operating means 27, which may be directed to the interior of the car. This valve is arranged to alternately open or close a cut-out opening 27, and the outlet conduit for air, in device 17 which leads to the interior of the car. Thus when it is desired to heat the car the valve is actuated to close the 85 cut-out opening 27, thus permitting heated air to pass out through the device 17 and into the car. When it is desired not to heat the car, the valve is actuated to close the outlet 17 and to open the cut-out 27. A 90 heater device of this kind, of course, is not utilized in summer and sometimes for several months the heated air is merely shut off by a grating in the interior of the car. The air within the heater becomes stagnant 95 and hot, and may result in over heating the heater resulting in undue deterioration of the parts and joints thereof. However, by utilizing the cut-out the hot air passes through the heater in the same manner as when the heater is used to heat the car, and in this manner the heater is in effect cooled by the passage of air therethrough.

It will be noted that the present invention affords a heater which is of a compact 100 nature for easy installation and in which certain portions are adjustable. The exhaust gases are contained entirely within the casting so that there is little or no danger of the leakage of the gases into the air to be 105 heated. It will be also noted that the air passes twice through the heater in directions transverse to the direction of the flow of the exhaust gases. In other words, the air passes down through the air passageways 110 and then up through the passageways. During this passage of air through the heater, the exhaust gases and the air are both divided into a plurality of streams alternately 115 arranged.

The taper of the walls of the longitudinally extending partition members not only aids in the casting of the interior heater unit, but has a definite effect upon the shape 120 of the passageways for the air (note Fig. 125 3). After the air enters the passageways 15 and 15^a the passageways become smaller and thereafter the air moves to the other side of the heater and passes upwardly the 125 passageways get larger. Cold air entering 130

the heater is, of course, expanded when heated. The higher degrees of heat in the air are attained, of course, as the air reaches the bottom of the heater and then passes upwardly and out of the heater. The air expands and due to the increasing capacity of the air channels a sort of draft is set up which aids the passage of air through the heater. Of course, when the air first enters the heater the passageways become smaller but the air at this point is only beginning to get warm and constriction of the passageways is not sufficient to offset the draft set up by the hot air passing out through the gradually enlarging passageways.

I claim:

1. An exhaust gas heater comprising a casting having an inlet and an outlet for exhaust gases disposed at opposite ends, a plurality of partitions in said casting for defining a plurality of passageways for the exhaust gases, said partitions each having passageways therethrough, a shell around the casting, said shell having an inlet and an outlet for air disposed near the ends of the heater, and a baffle within the passageway of each partition and located between the inlet and outlet openings of the shell whereby air which enters said casing is caused to flow through the passageways in the partitions across the path of the exhaust gases but out of contact therewith and then reverse and then again to flow across the path of the exhaust gases.

2. An exhaust gas heater comprising a casting having an inlet and an outlet for exhaust gases, a plurality of spaced hollow partitions in communication with the inlet and outlet for passage of exhaust gases therethrough, a shell around the casting having an inlet and an outlet for air arranged so that the air is passed transversely through the spaced partitions and then back transversely through the spaced partitions in a reverse direction, the walls of said partitions being divergent whereby the air passageways of the outgoing heated air are of gradually increasing capacity so that the expanded heated air sets up a draft to facilitate the passage of air therethrough.

3. An exhaust gas heater comprising a unit casting having at opposite ends a collar-like extension adapted for connection to an exhaust conduit, said casting having partitions therein which are hollow, whereby exhaust gases may pass through the casting between the hollow partitions, said partitions being separated from each other, a cas-

ing around this casting, said casing being spaced from the body of the casting and being connected thereto adjacent the collar-like extensions, said casing being provided with an inlet and an outlet for air whereby air may pass around the casting through the separated partitions and between the casing and the casting in heat transferring relation with the exhaust gases, and adjustable turrets in the said inlet and outlet openings in the casing for connection to air conduits.

4. An exhaust gas heater comprising a unit casting having at opposite ends a collar-like extension adapted for connection to an exhaust conduit, said casting having partitions therein which are hollow, whereby exhaust gases may pass through the casting between the hollow partitions, said partitions being separated from each other, a casing around this casting, said casing being spaced from the body of the casting and being connected thereto adjacent the collar-like extensions, said casing being provided with an inlet and an outlet for air whereby air may pass around the casting through the separated partitions and between the casing and the casting in heat transferring relation with the exhaust gases, and rotatably mounted turrets in the inlet and outlet casings each having an extension for connection to an air conduit.

5. An exhaust gas heater comprising a unit casting having at opposite ends a collar-like extension adapted for connection to an exhaust conduit, said casting having partitions therein which are hollow, whereby exhaust gases may pass between the casting through the hollow partitions, said partitions being separated from each other, a casing around this casting, said casing being spaced from the body of the casting and being connected thereto adjacent the collar-like extensions, said casing being provided with an inlet and an outlet for air whereby air may pass around the casting through the separated partitions and between the casing and the casting in heat transferring relation with the exhaust gases, said inlet and outlet openings being disposed on the same side of the casing and the said casting having baffle members within the divided partitions whereby the air is caused to pass through the partitions underneath the baffles and back again through the partitions.

In testimony whereof I affix my signature.
